UNITED STATES PATENT OFFICE.

JOHN SCOTT WILEY, OF HILLSBORO, ILLINOIS.

DEFLATING-TOOL FOR PNEUMATIC TIRES.

1,140,222.

Specification of Letters Patent. Patented May 18, 1915.

Application filed July 17, 1914. Serial No. 351,563.

To all whom it may concern:

Be it known that I, JOHN SCOTT WILEY, a citizen of the United States, residing at Hillsboro, in the county of Montgomery and State of Illinois, have invented certain new and useful Improvements in Deflating-Tools for Pneumatic Tires; and I do hereby declare the following to be a full, clear, and exact description of the invention, such as will enable others skilled in the art to which it appertains to make and use the same.

This invention comprehends certain new and useful improvements in deflating tools for pneumatic tires and has for its primary object to provide a tool of this character which may be readily applied to the valve stem and engaged with the tube within which the valve and valve stem are positioned to hold the tool against movement during the operation of deflating the tire.

This invention has for another object to provide a tool of this character which will be of such construction that it may be readily applied to the tube regardless of the size thereof and engaged against the valve stem to retain the valve in spaced relation with its seat to permit the air to escape from the tire.

The invention has for another object to provide a tool of this character which may be formed of resilient metal or the like, whereby the clamping arms will readily and automatically adjust themselves to the size of the tube within which the deflating tire is positioned to hold the tool against movement after the working end thereof has been engaged with the valve stem to retain the valve against movement and thereby prevent the valve from returning to its seat while the tool is in position.

The invention has for a further object to generally improve and simplify devices of this character and increase the efficiency thereof without materially increasing the cost of the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is an elevational view of an in-

flating tube of a pneumatic tire with my tool applied thereto, to retain the valve within the tube in operative position, Fig. 2 is a detail longitudinal section on the plane 60 of line 2—2 of Fig. 1, and Fig. 3 is a detail perspective view of the tool removed.

Referring in detail to the drawings by numerals, 1 designates the stem of my improved tool which has its parallel portions 65 inclosed by a sleeve 2 while its upper or outer end is turned at a right angle, and then directed downwardly and inwardly parallel with the main portion of the stem 1 as shown at 3 and 4 and finally turned outwardly to form the valve stem engaging finger 5.

The tool is formed of a single piece of wire or other resilient metal bent centrally upon itself to increase the strength of the 75 tool, the portions 1, 2, 3 and 4 being formed of the parallel legs of the wire, as will be readily understood by referring to the drawings. It will also be understood that the central portion of the wire forms the finger 80 4 and the parallel portions of the wire forming the body 1 are retained in proper position and held in engagement with one another by the sleeve 2, which is securely clamped around the stem 1 of the tool. 85

The free extremities of the wire forming the tool are extended beyond the lower or inner end of the sleeve 2 and bent at right angles to form the clamping arms 6 having their central portions curved outwardly in 90 opposite directions for clamping engagement around the valve tube 7 of a pneumatic tire or the like to hold the tool in proper position upon said tube with the valve stem engaging finger 5 pressing against the outer 95 end of the valve stem 8 within said tube 7 and thereby retaining said valve stem 8 and the valve 9 mounted upon the same in inoperative position to prevent said valve 9 from moving toward the valve seat 10 provided for the same in said tube 7 during the operation of deflating the tire or other device in which the tube 7 is extended. The free extremities 11 of the clamping arm 6 are flared outwardly in order that said clamping arm 105 6 may be readily engaged with and clamped around the tube 7.

From the foregoing it will be readily seen that this form of tool may be readily employed in connection with various types and 110 sizes of tubes 7 and valves 9 and valve stems 8 and will be highly efficient in use as the

clamping arms 6 will automatically and securely clamp the tool in position upon either a threaded or smooth tube and upon tubes 7 of various diameters.

5 While I have shown and described the preferred embodiment of my invention, it will be understood that minor changes in the details of construction, combination and arrangement of parts may be made without 10 departing from the spirit and scope of the invention as claimed.

What is claimed is:

1. A tool of the character described comprising a shank having one end bent at right angles and then parallel with the main portion of the shank, a valve stem engaging finger extended from the last mentioned portion and formed on said end, and tube clamping arms formed by the opposite 20 furcated end of said shank.

2. A device of the class described comprising a tool stem, clamping arms carried by one end of said stem to engage a tube, a valve stem engaging finger carried by the 25 opposite end of said tool stem to retain a valve stem and valve within the tube in inoperative position.

3. A device of the class described comprising a tool formed of resilient material and 30 consisting of a stem having clamping arms projecting laterally from one end for engagement with a valve tube to clamp the tool in position upon a valve tube, the opposite end of said stem being bent for engagement over the end of the tube upon which 35

the clamping arms are engaged, a valve stem engaging finger extended from the last mentioned end of said stem of the tool to retain the valve stem and the valve mounted thereon in inoperative position, and a protecting 40 sleeve engaged around the main portion of said stem of the tool.

4. A tool of the character described comprising a single piece of resilient metal bent centrally upon itself to place the legs thereof parallel with one another, the main portions of said legs forming the stem of the tool, the connected ends of said legs being extended at an angle from one end of said stem and turned parallel with said stem, the 50 connected ends of said legs being bent to form a valve stem engaging finger to retain a valve within a valve tube in inoperative position, the free ends of said legs being extended laterally from the opposite end of 55 said stem of the tool and curved in opposite directions to form clamping arms with their free extremities flared outwardly to permit said clamping arms to be readily engaged around the tube of the valve, said arms serving to retain the tool in operative position, and a sleeve engaged around the central portions of the legs forming the stem to retain said legs against spreading.

In testimony whereof I affix my signature 60 in presence of two witnesses.

JOHN SCOTT WILEY.
